United States Patent

Des. 234,922
Patented Apr. 15, 1975

234,922

AUTOMOBILE BODY

Edward Allen Newton, Worthington, Ohio, assignor to
Roach Studios, Inc., Worthington, Ohio

Filed Jan. 5, 1973, Ser. No. 321,217

Term of patent 14 years

Int. Cl. D12—08

U.S. Cl. D12—86

FIG. 1

FIG. 2

FIG. 1

FIG. 2

FIG. 3

FIG. 1 is a front perspective view of an automobile body embodying my new design.

FIG. 2 is a top plan view thereof.

FIG. 3 is a side elevational view thereof.

FIG. 4 is a front elevational view thereof.

FIG. 5 is a rear elevational view thereof.

The broken lines in the drawing are for illustrative purposes only.

I claim:

The ornamental design for an automobile body, substantially as shown and described.
